MOBILE ADJUSTABLE STAND FOR FANS

Viktor Schreckengost, Cleveland Heights, Ohio, assignor to The Murray Ohio Manufacturing Company, Nashville, Tenn., a corporation of Ohio

Filed Mar. 28, 1962, Ser. No. 69,471

Term of patent 14 years

(Cl. D14—3)

FIG. 1

FIG. 1 is a top plan view of a mobile adjustable stand for fans, showing my new design; and

FIG. 2 is a perspective view of the stand illustrated in FIG. 1.

The side and end not shown are identical to the side and end shown.

The portions shown in broken lines are included for illustration purposes only.

I claim:

The ornamental design for a mobile adjustable stand for fans, substantially as shown and described.
